REFLECTING SIGN FOR ROADS AND
STREETS

Albert Wood, London, England,

Refiled for application Serial No. 673,295, May 27,
1933. This application January 27, 1934, Serial
No. 708,670. In Great Britain May 3, 1932

4 Claims. (Cl. 40—135)

This invention relates to reflecting signs for roads and streets which at night are illuminated by an external source of light such as the lamps of the road, shops, or of approaching vehicles. In such signs as used hitherto, the reflected light is dispersed over such a wide area, that the luminosity of the sign in any one direction is of relatively low value, and the observer must therefore approach much nearer to the sign before it becomes legible than would be necessary if the apparent luminosity of the sign were of higher value.

The object of the invention is to provide a reflecting sign which shall reflect a larger proportion of the rays in a direction nearly parallel to the incident rays than has been the case hitherto, whereby the sign shall be legible to an observer at a greater distance therefrom than has been the case hitherto.

The invention consists in the use, in combination with the matter to be displayed, of a light-condensing plate of clear glass or other transparent material, the front face of which is provided with a plurality of small lenses of spherical or paraboloidal surface the foci of which are at or near the other or plane face of the plate, and a dispersively reflecting surface at said plane face.

The light-condensing plate and the matter to be displayed are held in a suitable frame.

Drawings are appended diagrammatically illustrating the invention.

Figure 1 is a fragmentary section of a sign wherein the displayed matter is in the form of a flat sheet held between the light-condensing plate and the back of the frame.

Figure 2 is a fragmentary section of a sign wherein the displayed matter is in the form of a stencil held against the lenticular face of the light-condensing plate.

Figure 3 is a fragmentary section of a sign wherein the displayed matter is painted on the lenticular face of the light-condensing plate.

Figure 4 is a diagram illustrating the action of the device.

Figures 5 and 6 are fragmentary views looking at the front of the sign, illustrating the appearance of the brightly illuminated parts in relation to the parts darkened by the displayed matter, Figure 5 being for a sign as shown in Figure 3, painted, Figure 6 being for a sign as shown in Figure 2.

The invention can be carried into effect in various forms, but in all forms the lenticular face of the light-condensing plate faces outward to-

ward the source of light. In one form, Figure 1, the matter to be displayed is prepared on a flat sheet 1 such as a billposter, which in itself forms the dispersively reflecting surface, and is placed against the back 2 of the frame. The plane face 60 of the light-condensing plate 3 is placed in close contact therewith. This form can be used for direction and warning signs, and is also particularly advantageous for advertising signs, since the displayed matter can be changed as often as 65 may be desired.

In another form Figure 3, the matter 6 to be displayed is painted or otherwise affixed to the lenticular face of the light-condensing plate, and the plane face of the plate is treated with a 70 white matt reflecting surface 7, for example plaster-of-Paris. Or, alternative to such treatment, the back of the frame may be painted a matt white surface, or a plain sheet of white paper may be held in the frame, the plane face of 75 the light-condensing plate being placed in contact therewith.

In another form, Figure 2, the matter to be displayed is prepared in the form of a stencil 4, which is held against the lenticular face of 80 the light-condensing plate 3 whose plane face is treated as just described. A cover plate 5 of plain clear glass or other transparent material may be used to hold and protect the stencil.

From the description of the few forms given 85 above, it is obvious that other forms modified therefrom can be used.

In Figure 4, the source of light is supposed to be the head lamp or lamps of an approaching vehicle, the rays r of the incident beam of light 90 being then practically parallel. The action of the device is as follows:—The light-condensing plate concentrates the incident light from the lamps in front of the sign or of an approaching vehicle on to the surface in contact with its 95 posterior face in a series of brilliantly illuminated spots, the rest of said surface being left dark. More precisely, considering only one lens 7 of the light-condensing plate and the corre-

100 sponding luminous spot s , Figure 3, each ray r incident thereon is refracted at the lens 7 and dispersively reflected from the luminous spot s , and the dispersed reflected rays r_1 are nearly all condensed by the same lens. These condensed rays from all the rays r emerge as a slightly 105 divergent beam of light r_2 , of which the axis of maximum intensity is practically parallel to that of the incident rays. The aggregate effect, as shown in Figures 5 and 6, is substantially uniform illumination of the clear portions of the 110

sign, a very close inspection being required to distinguish the individual portions due to the individual lenses.

5 The luminosity of the sign as viewed by an observer will be greater the closer he is to the said axis of maximum intensity. In the case of an approaching vehicle whose head lamps illuminate the sign, the luminosity as viewed by the driver is the greatest possible.

10 It is to be observed that if the reflecting surface behind the light-condensing plate is a mirror or the like giving the angle of reflection equal to that of incidence, the desired effect as described is not produced.

15 I claim:

1. In a reflector sign for illumination by an external source of light, a light-condensing plate of transparent material the rear face of which is plane and the front face of which is provided 20 with a plurality of small lenses of convex external surface the foci of which are at the plane face of the plate, and a medium providing a dispersively reflecting surface at said plane face.

2. In a reflector sign for illumination by an external source of light, a light-condensing plate 25 of transparent material the rear face of which is plane and the front face of which is provided

with a plurality of small lenses of convex external surface the foci of which are at the plane face of the plate, and a sheet containing the matter to be displayed placed in close contact with said plane face.

3. In a reflector sign for illumination by an external source of light, a light-condensing plate of transparent material the rear face of which is plane and the front face of which is provided 85 with a plurality of small lenses of convex external surface the foci of which are at the plane face of the plate, displayed matter painted on the lenticular face of the plate, and a medium providing a white dispersively reflecting surface at said plane face.

4. In a reflector sign for illumination by an external source of light, a light-condensing plate of transparent material the rear face of which is plane and the front face of which is provided 90 with a plurality of small lenses of convex external surface the foci of which are at the plane face of the plate; a medium providing a white dispersively reflecting surface at said plane face, a stencil in front of the light condensing plate, and a cover plate of transparent material in front 95 of the stencil
